T. L. Boyden
Inventor.

UNITED STATES PATENT OFFICE.

THOMAS L. BOYDEN, OF VICTORIA, BRITISH COLUMBIA, CANADA, ASSIGNOR OF ONE-HALF TO JOHN HART, OF VANCOUVER, CANADA, AND HENRY C. HALL, OF VICTORIA, CANADA.

REFLECTING-SIGNAL DEVICE.

Application filed December 16, 1926, Serial No. 155,239, and in Canada December 17, 1925.

This invention relates to reflecting signal devices such as are employed at abrupt turns or other danger points on highways to intercept the beam of light from an approaching automobile headlight and after filtering the same through a suitable medium reflect it back as a danger signal.

Its objects are to provide such a device in a more efficient as well as cheaper form than those hitherto in vogue, and particularly to produce a warning signal which shall have a measure of scintillating effect and therefore of a more arresting character to an approaching vehicle.

15 I am aware that there are now in use signal reflectors for the same general purpose but they are not adapted to so readily intercept and reflect light rays from vehicles approaching at various angles as can be effected by my device.

In the drawings herewith which form part of this application Fig. 1 is a plan view of my reflecting device, shown with the right hand half of the faceplate removed, Fig. 2 being a cross section on line A—B, and Fig. 25 3 a similar cross section but showing a variant in the form of the face-plate.

The reflecting member of the device consists of a series of square pyramids (a) arranged side by side in both directions, and mounted on a plane surface either flat or curved. The pyramids are identical and their vertices are so arranged that the sides of adjacent and opposite pyramids make angles of 90 degrees with each other as shown at (b). The reflecting member may be of any material suitable for the purpose, but I prefer to employ glass coated at the back (c) with the mercury composition usually employed for mirrors, the composition being afterwards sealed with bitumen or other suitable damp-resisting compound to exclude the possibility of deterioration by moisture. The reflecting member is mounted in a suitable 35 casing (d) and is secured by the clamping member (e) and the gasket (f) the latter being held by the glass face-plate (g) the gasket (h) intervening.

The face-plate (g) is divided checker-board fashion as shown, with alternate squares of red glass or other similar medium, so that the incident light rays passing through it are reflected back as a warning signal.

In Fig. 3 the glass face-plate (i) is made with a curvature, the plane (j) of the bases of the pyramids being made parallel to the face-plate (i). The clear portions of the checker-board arrangement on the face-plate being embossed so as to form the convex lenses (k).

By this arrangement an effect of a scintillating character is obtained, adding greatly to the arresting power of the signal. Moreover the light rays from a larger angular field are intercepted and made available as a warning signal, than is possible with reflectors of this class which are now in vogue.

What I claim as my invention and desire to secure by Letters Patent, is:

1. In a signaling reflector of the type described, the combination comprising: a reflector having a multiform surface produced by a series of square pyramids, the bases of said pyramids being placed side by side in both directions, the said pyramids being so proportioned that adjacent and opposite sides of any two pyramids form an angle of 90 degrees with each other, the said reflector being covered by a transparent face-plate, the said face-plate being sub-divided into alternate clear and colored squares, the said squares corresponding to and being coincident with and opposite to the bases of the said pyramids thus producing a "checker-board" arrangement.

2. In a signaling reflector of the type described the combination comprising, a glass reflector consisting of a series of square pyramids, the bases of said pyramids being placed side by side in both directions, the said pyramids being so proportioned that the adjacent and opposite sides of any two pyramids form an angle of 90 degrees with each other, the said reflector being coated on one side with the metallic composition usually employed for producing mirrors, the said composition being covered with a moisture resisting paint, the face of the said reflector being covered by a transparent plate, the said plate being subdivided into alternate clear and colored squares corresponding to and being coincident with and opposite to the bases of the said pyramids.

3. In a signaling reflector of the type described the combination comprising: a multifacet reflecting surface of the type described in claim 2, but in which the plane

- of the bases of the said pyramids is curved, a transparent face-plate covering the said reflecting surface and parallel to the said plane of the bases of the said pyramids, the 5 said face-plate being subdivided into alternate clear and colored squares, the said squares corresponding to and being coincident with and opposite to the bases of the said pyramids.
- 10 4. In a signaling reflector of the type described the combination comprising; a reflector having a multiform surface produced by a series of square pyramids, the bases of said pyramids being adjacent each other in 15 both directions, the said pyramids being so

proportioned that adjacent and opposite sides of any two pyramids form an angle of 90 degrees with each other, the said reflector being coated on one side with the metallic salt commonly used for mirrors, the face of 20 said reflector being covered by a transparent plate, the said plate being subdivided into alternate clear and colored squares, the said squares corresponding to and being coincident with and opposite to the bases of the 25 said pyramids, the said clear squares being embossed with a lens-like projection, all substantially as described and shown.

THOMAS L. BOYDEN.
